UNITED STATES PATENT OFFICE.

ADOLPH C. RECKER, OF OAKVILLE, CONNECTICUT, ASSIGNOR TO CHASE COMPANIES INC., OF WATERBURY, CONNECTICUT, A CORPORATION.

CASING FOR ELECTRIC-LAMP SOCKETS.

Application filed September 4, 1926. Serial No. 133,567.

My invention relates to an improved casing for electric lamp-sockets, the object being to provide a simple and effective means for locking the cap and shell of such a casing against being pulled apart axially and against relative rotative movement, the said means being designed with particular reference to convenience of manipulation, to the avoidance of weakening the shell and the cap, and to securing a casing of neat and attractive appearance.

With these ends in view, my invention consists in a cap for the casings of electric lamp-sockets, the said cap having certain details of construction as will be hereinafter described and particularly pointed out in the claim.

In the accompanying drawings:

Fig. 1 is a view in side elevation of a casing for electric lamp-sockets constructed in accordance with my invention;

Fig. 2 is a similar view with the cap and shell separated from each other, but arranged in line;

Fig. 3 is a view of the cap and shell in transverse section on the line 3—3 of Fig. 1;

Fig. 4 is an enlarged segment of Fig. 3;

Fig. 5 is a detached reverse plan view of the cap; and

Fig. 6 is a broken, sectional view on the line 30 6—6 of Fig. 1.

In carrying out my invention, as herein shown, the cap 10 and shell 11, which together constitute the socket-casing, have the general form of the corresponding parts of standard electric-lamp socket-casings. The upper edge of the shell 11 is struck up so as to form well-defined axial locking-ribs 12, separated by axial channels 13 wider than the extreme width of the said ribs 12 at the bases thereof.

40 This series of ribs and channels is interrupted by a deep key-slot 14, which provides not only for the usual key, but also for the springing of the shell necessary to disengage it from the cap. In socket-casings requiring no key-

45 slot, such as 14, the shell must be slit to permit it to be sprung and so separated from the cap. At a point close to one edge of the key-slot 14, or the slit employed in place thereof, the shell is furnished with two outwardly-

50 extending locking-projections 15 symmetrically located toward the lower ends of two of the said channels and having parallel straight cut edges facing downwardly in a plane at a right angle to the axis of the shell.

55 Another pair of projections 15 is formed in

the shell at a point diametrically opposite the projections 15 described, as shown in Fig. 3.

The cap 10 is formed with a plain, imperforate flange 16 and is so described to distinguish it from caps having actual perforations which are concealed by a supplemental band applied over the flange 16. The lower edge of the flange 16 is struck up to form a continuous series of inwardly-extending locking-projections 17, the cut upper edges 18 of which are straight and located in line in a plane at a right angle to the axis of the cap. As shown, these locking-projections 17 are triangular in form. That form, however, is not essential, but it is essential that their cut upper edges shall be straight and in line as specified.

At a point above this continuous line or fillet of locking-projections 17, the flange of the cap is provided at opposite points in its circumference with a pair of inwardly-extending struck-up locking-projections 19 having straight cut edges facing each other in planes parallel with the axis of the cap. As shown, these locking-projections 19 are 80 triangular, but that form is not essential, although it is essential that they shall have straight locking-edges facing each other in planes parallel with the axis of the cap. I have shown two pairs of these anti-rotary 85 locking-projections 19, but one pair would suffice and more than two pairs may be employed if preferred.

It will be seen by reference to Fig. 2, that the ribs 12 and channels 13 are long enough 90 with reference to the width of the flange 16 and the location of the projections 19 therein, so that when the cap and shell are telescoped one into the other, the outer ends of any two pairs of adjacent ribs 12 of the shell will be 95 in position to engage with the cut edges 20 of the anti-rotary projections 19 of the cap, of which there are two pairs.

It will be understood that when the ribbed upper end of the shell is inserted into the 100 flange of the cap, or vice versa, and the two parts pushed "home," irrespective of their relative rotary position, a pair of the ribs 12, at opposite points in the shell, will be inserted between the straight locking-edges 20 105 of the projections 19 of the two pairs of such projections whereby the relative rotary movement of the cap and shell is thereafter effectually resisted. At the same time, the straight locking-edges of the two pairs of 110

locking-projections 15 of the shell will ride over the straight locking-edges of two pairs of the locking-projections 17 of the cap, whereby the cap and shell will be locked together and so prevented from being pulled apart in line with their axes.

It will thus be seen that the locking of the cap and shell against relative rotary movement is devolved upon the ribs 12 of the shell 10 and the anti-rotary locking-projections 19 of the cap and that the locking of the cap and shell against being pulled apart is devolved upon certain pairs of the locking-projections 17 of the cap in conjunction with the two 15 pairs of locking-projections 15 struck out of the bottoms of two pairs of the channels 13 in the shell.

To disengage the cap and shell, it is only necessary to exert pressure upon the shell at 20 a point close to the edge of its slot 14 on the side of the projections 15, which are thus sprung sufficiently inward for the clearance of their straight cut lower edges from the straight cut upper edges 18 of two of the 25 locking-projections in the cap, after which, by a slight tilting of the cap or shell, or both, they are readily drawn apart.

In the construction shown and described, the size and spacing apart of the ribs 12 and 20 the size and spacing apart of the inwardly-extending locking-projections 17 is such that when the cap and shell are combined, the upper corners 21 of the said projections will engage with the sides of the ribs in such a 35 manner as to resist, to a very marked degree, the relative rotation of the cap and shell, which, on account of such engagement, cannot be relatively rotated without exerting upon them sufficient twisting strain to cause the 40 said corners to compress the metal of the shell to enable the corners to ride over the ribs. However, to guard against that contingency, I provide two pairs of anti-rotary locking-projections 18, the relatively long straight cut 45 edges 19 of which facing each other engage with the long sides of the ribs 12, so as to constitute positive stops against relative rota-

tion, no matter how strong the twisting strains imposed upon the cap and shell, which, when assembled with the fittings which they are 50 designed to encase, have little capacity for being sprung.

I claim:

In a casing for electric lamp sockets, the combination with a sheet metal shell having 55 its open upper edge formed with a continuous band of longitudinal locking-ribs separated by longitudinal channels and having a longitudinal slit to permit the shell to be inwardly sprung at a point adjacent thereto, 60 and also formed with a pair of outwardly-extending locking projections located toward the lower ends of two of the said channels and having parallel straight-cut edges 65 facing downward in a plane at a right angle to the axis of the shell; of a cap for the said shell having an unbanded, imperforate flange formed adjacent to its edge with a continuous band of inwardly-struck locking projections, 70 the cut upper edges of which are in line with each other in a plane at a right angle to the axis of the cap, and the said cap being also provided at a point above the said band of locking projections with one or more pairs 75 of inwardly-struck anti-rotary projections having straight-cut edges facing each other in planes parallel with the axis of the cap, the said continuous band of inwardly-struck locking projections of the cap being positioned to coact with the said outwardly-struck 80 pair of projections in the channels of the shell, and the said anti-rotary projections of the cap being positioned to coact with certain of the said locking-ribs of the shell for preventing the cap and shell from relative rotation 85 when certain of the inwardly-struck locking projections of the cap are engaged with the outwardly-struck locking projections of the shell to prevent the axial separation of the cap and shell.

In testimony whereof I have signed this 90 specification.

ADOLPH C. RECKER.
